UNITED STATES PATENT OFFICE.

ALY I. SCHALL, OF YONKERS, NEW YORK.

AUTOMATIC FIRE-SPRINKLER.

1,010,078.

Specification of Letters Patent. Patented Nov. 28, 1911.

Application filed September 14, 1911. Serial No. 649,327.

To all whom it may concern:

Be it known that I, ALY I. SCHALL, a subject of the Emperor of Austria-Hungary, and a resident of Yonkers, in the county of 5 Westchester and State of New York, have invented certain new and useful Improvements in Automatic Fire-Sprinklers, of which the following is a specification.

My invention relates to fire extinguishers, 10 and particularly to devices of this character intended to automatically sprinkle or spray water or other substances, and its objects are, among others, to produce a device of this character of relatively simple and durable construction, which will act with greater 15 certainty and protect a greater zone or area from fire.

The invention consists in the construction, 20 combination and arrangement of parts hereinafter described and claimed and illustrated in the accompanying drawings.

In the said drawings Figure 1 is a bottom plan of a fire extinguishing sprinkler embodying the improvements, and Fig. 2 is 25 a vertical section of the same on the line 2—2 of Fig. 1, looking in the direction indicated by the arrows in that figure, and showing the device inverted.

The inlet tube A is adapted to be connected with a water-main or other source 30 of supply of fire extinguishing fluid, and communicates with a central chamber B, having a vent in its bottom consisting of a foraminous cone C, provided with a cap D, 35 covering and closing the same. From this central chamber B extend four horizontal hollow arms F, each arm provided with a hollow head G, provided with a vent H, consisting of a foraminous cone C, and closed 40 by a cap J, similar to the cap D. The caps D and J fit the exterior of their respective cones very closely, and are, in fact, ground so as to coincide therewith exactly. The inner edge of the cap, however, does not 45 quite come in contact with the base of the cone, and an annular space K is, therefore, left between the said inner edge and base. These caps are normally held in position by struts L and M, made of fusible metal and 50 provided with a conical tip at one end, fitting a depression in the cap and a recess at the opposite end to receive the point of the thumb-screw plug N, by which pressure is applied thereto and the cap thus pressed 55 firmly against the perforated cone. The thumb-screws N intermesh with threaded

apertures in the brackets O and P, the bracket O being threaded to the exterior of the chamber B, and the brackets P to the exterior of the heads G. When the fusible 60 struts L release the caps they fall off of their own weight, accelerated by the pressure from within, and in order to prevent loss of these caps, they are connected to the sprinkler by means of chains R, secured at 65 one end to a collar R' on the cap, and the other end to a collar R'', which in the case of the caps closing the orifices of the arms are strung on the arms F, and in the case of the cap closing the bottom orifice of the 70 chamber B surrounds one branch of the bracket O.

It will be noted that the construction herein described is one of extreme strength and simplicity, and that the parts are interchangeable. The construction is also such that the sprinklers may be assembled or dismembered without the use of tools or the making or breaking of permanent joints, and it is with these ends in view that the hollow 75 arms F are made in two sections, F' and F'', connected by means of the internally screw-threaded enlargement F³ at the inner end of the section F'', which receives the externally threaded section F', and provides a 80 beveled seat for its extreme inner edge; that the brackets O and P are threaded on the exterior of the central chamber B and the hollow heads G respectively; and that the caps D and conical sprinkler vents C are 85 90 the same size.

It is a very simple matter for the engineer of a large building fitted with this apparatus to make repairs after a fire, from a stock of parts kept on hand, or to set up 95 new sprinklers in different parts of the building, and, in fact, this work can be done, and done properly, by persons not at all familiar with mechanical appliances. In addition to these and other advantages, the 100 sprinkler possesses the great advantage of covering an extensive area, and thus protecting it from fire. The number of sprinkler heads connected with the central chamber B may be varied, and one or two or 105 more may be plugged up, where the sprinkler is located in a corner or some other place where sprinkling in one general direction only is desired. There are also other advantages which will be obvious to those familiar 110 with this art, among which is the advantage afforded by the method of attaching the

brackets to the frame of the sprinkler, which gives an additional adjustment of the parts connected therewith.

The collar R' is connected with the chain R by means of a small arm R³, projecting from the collar, and provided with an in-turned flange R⁵, which spaces it from the cap, and a small screw-bolt R⁴ which passes through the arm and engages the end link of the chain. With this arrangement the cap with its collar may be placed in position and the chain then connected with the collar.

What I claim is:

15 1. A device of the character described, comprising a central chamber, means for connecting the said chamber with a source of fluid supply, a plurality of hollow arms extending horizontally from said chamber, said arms being formed in two detachable sections, a hollow head on the end of each arm, a conical perforated portion on said head, a complemental cap fitting said perforated conical portion, a bracket surrounding said cap, a fusible strut, an adjustable member secured to said bracket, by the movement of which the said strut may be pressed against the said cap or withdrawn therefrom.

30 2. A device of the character described, comprising a central chamber, means for connecting the said chamber with a source

of fluid supply, a plurality of hollow arms extending horizontally from said chamber, 35 said arms being formed in two detachable sections, a hollow head on the end of each arm, a conical perforated portion on said head, a complemental cap fitting said perforated conical portion, a bracket surrounding 40 said cap, a fusible strut, an adjustable member secured to said bracket, by the movement of which the said strut may be pressed against the said cap or withdrawn therefrom, and a perforated conical vent in the bottom of said central chamber and a 45 cap covering the same, both parts being substantially identical with the first claimed conical portions and caps.

3. In a device of the character described the combination of a perforated cone, a cap 50 covering said cone and closing the perforations, a collar on said cap, an arm projecting from said collar, means for spacing said arm from the cap, and means for connecting the said arm to a chain or other flexible member, 55 whereby the said cap is held connected to the device after it has been displaced.

Witness my hand this 11th day of September, 1911, at the city of New York, in the county and State of New York.

ALY I. SCHALL.
